SNUBBING MECHANISM

Emil H. Blattner, Buffalo, N. Y., assignor to The Symington-Gould Corporation, Depew, N. Y., a corporation of Maryland

Application March 31, 1950, Serial No. 153,121

13 Claims. (Cl. 267—9)

This invention pertains to a snubbing mechanism and 15 more particularly to a type thereof adapted to be employed as a component of a railway truck.

An object of the invention is the provision of an improved snubbing mechanism of a unitary character having, in association, a group of coil springs and a friction creating device.

Another object of the invention is the provision of an improved snubbing mechanism wherein a pair of plates are resiliently held apart and arranged with a built-in friction creating device forming a component thereof.

A further object of the invention is the provision of an improved snubbing mechanism wherein a pair of vertically spaced plates have associated therewith a group of all coil springs and a friction creating device, with the plates being arranged for relative horizontal movement in all directions without disturbing the effectiveness of the all coil springs or friction creating device.

These and many other objects of the invention will be apparent from the succeeding description considered together with an exemplified form of the invention illustrated in the accompanying drawings wherein:

Figure 1 is a partial plan and partial sectional view of a snubbing mechanism embodying the present invention.

Figure 2 is a partial vertical sectional view and a partial elevational view taken along the lines 2—2 of Figure 1 40 looking in the direction of the arrows.

Figure 3 is a partial vertical sectional view and a partial elevational view taken along the lines 3—3 of Figure 1 looking in the direction of the arrows.

Figure 4 is a horizontal sectional view taken along the lines 4—4 of Figure 2 looking in the direction of the arrows.

Figure 5 is a horizontal sectional view taken along the lines 5—5 of Figure 2 looking in the direction of the arrows.

Referring now in detail to the drawings wherein like reference characters indicate like parts the numeral 1 is employed to designate, in a somewhat general manner, a snubbing mechanism or spring group illustrative of the present invention. The snubbing mechanism is employed, as indicated in the preamble hereof, as a component of a railway truck and as such is positioned as a separate unit between a bolster only a bottom surface of which is indicated in the drawings by a diagrammatic line 2 and a side frame or spring plank indicated by diagrammatic line 3. The function of the snubbing mechanism is to cushion external impulses imparted to the side frame or spring plank so that such impulses or at least the full magnitude thereof will not be transmitted to the bolster. The snubbing mechanism comprises a bottom or spring plate 4 having a bed plate 5 thereof substantially flat so as to rest fully or bear upon the side frame or spring plank. The bed plate has certain portions of its periphery of circular formation as at 6 and this part of the periphery has an upstanding flange 7 for the purpose which will hereinafter be made apparent. Spaced a predetermined distance above the bottom plate is a top or spring plate 8

2

formed in part by a cover plate 9 which, for its most part, is substantially flat to form an adequate seat for the superimposed bolster. In like manner, the cover plate is provided with a portion of its periphery circular in formation and having, at this portion, a downstanding flange 10.

Disposed between the top and bottom plates is a nest or group of all coil compression springs 11 arranged to resiliently carry the load imposed thereon by the truck bolster. The circular portions of the spring plates are formed to follow the adjacent contour of the coil springs and the hereinbefore recited flanges function as confining means to prevent a horizontal shifting of the coil springs from a predetermined position. All coil or helical springs are employed as the yieldable or resilient means between the top and bottom plates because of their fast acting, easy riding characteristics. While this feature is highly desirable it has been found in actual practice that when all coil springs are employed for the purpose of supporting a truck bolster, the external impulses to which the structure is subjected in service at certain times synchronize with the vibrations of the springs. This harmonic action of impulses and vibrations results in the coil springs being driven solid to thereby impart intensified blows to the structure with the resultant damaging effects.

Some means should be associated with the springs to check, retard or disturb the natural vibrations thereof and toward this end the bottom plate has formed, as an integral part thereof, a housing or casing 12. This housing upstands vertically from the bed plate adjacent the center thereof between the coil springs. Mainly, the casing comprises a pair of horizontally spaced, preferably vertical and parallel end walls 13 joined by horizontally spaced confining walls 14 to present a fully enclosed area clearly opening particularly upwardly or toward the top plate. It is to be noted that the confining walls, while joining related extremities of the end walls in a reinforcing manner are curved or bulged as at 15 to follow the contour of the adjacent coil springs to assist in retaining the latter in a somewhat fixed position as well as permit the end walls to extend horizontally for their full or an appreciable extent. Further the confining walls are reinforced by means of triangular gussets 16 which also merge with or outstand from the bed plate intermediate the ends of the confining walls. In like manner the bearing walls are reinforced by braces 16a which are formed integrally with the bed plate and bearing walls. Since the end walls function as bearing walls, as will be hereinafter brought out, it is believed preferable to provide these walls with bearing plates 17 of hardened steel as opposed to the cast steel of the bottom spring plate. These bearing plates positioned on the inside of the casing are subjected to wear and in order to render them replaceable they are conveniently fastened to the end walls by means of welds 18 or any other desired holding medium. Each bearing plate presents a brushing face 19 exposed inwardly of the casing so that a pair of brushing faces is oppositely disposed and face one another in spaced relation within the confines of the housing or casing.

Positioned within the casing and arranged to be moved vertically therein is a pair of counterpart shoes 20 desirably of cast form. The shoes are spaced apart horizontally and each have along one side thereof, a rubbing face or surface 21 in frictional or intimate contact with a related bearing plate face so that, as the shoes are moved vertically, frictional forces will be created on the contiguous faces to disturb or control the harmonic actions of the all coil springs. Further, each shoe is provided with a knob, projection or protuberance 22 disposed intermediate its height and width and extending in a direction inwardly of the casing so that the protuberances of oppositely disposed shoes project toward one another.

The top spring plate has, at its central area, an opening 23 extending entirely therethrough and this opening is defined by horizontally spaced legs or end walls 24 normally and desirably positioned or disposed in vertical alignment with the subjacent or lower spaced shoes. Joining related extremities of the legs is a pair of parallel connecting walls 25 with these walls being suitably reinforced by triangular gussets 26. The end and connecting walls downstand from the top plate into the confines of the spring unit or snubbing mechanism but, however, terminate short of the bottom plate walls for the purpose to be hereinafter made apparent. Each leg is also provided with a knob or protuberance 27 which extends inwardly of the device so that these top cap protuberances also extend toward one another and in substantial vertical alignment with the shoe protuberances.

As will be appreciated the lower or bottom spring plate remains stationary with respect to the side frame or spring plank and the top spring plate or cap is arranged, during the flexing action of the coil springs, to move vertically toward or away from the lower spring plate. Accordingly, in order to reflect a vertical movement of the top spring plate in the shoes to create the necessary or required frictional forces, there is incorporated in the device a pair of connecting links or arms 28. Each link is spaced horizontally from a companion or related link and extends vertically so as to join vertically aligned or related protuberances and since the links are rigid or stiff components, any vertical movement of the top spring plate will cause the shoes to execute a like or corresponding vertical movement.

It has been found in practice that a bolster besides moving vertically relative to a side frame or spring plank also is caused to move horizontally in all directions, at least for the value of the clearances allowed between interlocking parts of the side frame and bolster. If structure is not incorporated in the device to compensate for this referred to horizontal movement, then the components of the device will be subjected to stresses for which they may have not been designed to withstand. Also the relative movable parts of the device may not, and in all probability will not function as intended. Accordingly, the protuberances of the shoes are formed circular or convex and as such present ball or spherical surfaces 29 and these shoe surfaces nest in ball or spherical concave surfaces 30 formed in the lower extremities of the links. This relation or association of ball and socket surfaces not only forms a positive and definite interlock between the shoes and links but also affords universal movements between these components. Each top plate knob 27 is also formed as a convex or spherical ball shaped surface 31 so as to nest with a concave, spherical, socket shaped surface 32 in a related extremity of a link and a universal movement may be also freely executed by this connection. With this construction, therefore, any vertical movement of the top plate will result in a vertical movement of the shoes and any horizontal movement of the top plate will not disturb the prearranged relationship of the surfaces 19 and 21.

In order to exert the required pressure against the links, the latter are provided with horizontally aligned upper and lower studs 33 and 33a respectively with these studs desirably positioned on the vertical center line of the links. An upper coil or helical spring 34 has a horizontal axis extending between the upper limits of the links to be in overlapping relation with the upper studs thus keeping the upper coil spring in position and maintaining constant contact between ball and socket surfaces 31 and 32. Disposed parallel with the upper coil spring is a lower coil spring 35 which, at its ends telescopes the lower studs to thereby be held in a predetermined position. The lower coil spring being compressed between the lower extremities of the links not only maintains a contact of the ball and socket surfaces 29 and 30 but also exerts sufficient pressure to cause the required amount of frictional forces

to be created on the shoe rubbing faces and the housing brushing faces for snubbing or controlling the vibrations of the all coil springs.

It may at times be thought necessary to limit the movement of the shoes relative to the levers. If such is deemed necessary each link may be provided with a post or shaft 36 centrally disposed between the link sockets and extending in a direction away from the link toward a related or companion housing bearing wall. This construction necessarily infringes on the shoe area by extending into the confines of the shoes. Accordingly each shoe has, formed therein, a U-shaped opening or slot 37 and as will be noted by referring particularly to Figures 3 and 4 of the drawings, each post extends freely into a related or adjacent slot with sufficient clearance thereabout to permit or allow a required universal movement between the links and shoes.

For the purpose of assembly of the unit each post, at its free extremity, has a shallow well 38 formed therein so that during assembly, a proper tool (not shown) may be seated in the wells and the links be moved toward one another until the upper and lower coil springs are solid. This compressing of these springs will permit the insertion of the shoe-link-spring assembly within the lower spring plate casing and allow the top spring cap or plate to be lowered until the ball surfaces 31 are aligned with the sockets 32 at which time the tool may then be manipulated so that all the components of the device may assume normal positions as illustrated in the drawings.

From the above it will be noted that various changes and alterations may be made to the illustrated and described construction without departing from the spirit of this invention or scope of the appended claims.

I claim:

1. In a spring group for a railway car truck, the combination of, top and bottom spring plates, a group of coil springs between said plates, a housing upstanding from said bottom plate and presenting oppositely disposed walls, friction shoes within said housing and arranged to contact said walls, said shoes having convex surfaces, convex surfaces on said top plate above said shoe convex surfaces, connecting means extending between each top plate convex surface and related shoe convex surface and provided with concave surfaces accommodating said convex surfaces, and spring means urging said connecting means into contact with said top plate and shoes for maintaining the connection therebetween.

2. In a railway truck spring unit with a built-in snubber, the combination of, top and bottom spring plates, coil springs between said plates, horizontally spaced walls upstanding from said bottom plate, horizontally spaced shoes bearing against said walls, horizontally spaced means downstanding from said top plate, said last named means being spaced inwardly of said unit from the horizontal limits of said walls, a link connecting each downstanding means and related shoe and arranged to pivot relative thereto, and horizontal spring means between said links for urging the latter apart.

3. In a railway truck spring unit with a built-in snubber, the combination of, top and bottom spring plates, a group of coil springs between said plates, horizontally spaced vertically extending walls upstanding from said bottom plate, horizontally spaced shoes arranged to frictionally contact said walls, horizontally spaced legs downstanding from said top plate in substantial vertical alignment with said shoes, means connecting each leg and related shoe and arranged for angular movement therebetween, and spring means between said connecting means for urging said connecting means apart.

4. In a railway truck spring unit with a built-in snubber, the combination of, top and bottom spring plates, a group of coil springs between said plates, a housing presenting horizontally spaced walls upstanding from said bottom plate, horizontally spaced shoes arranged

to frictionally engage said walls, horizontally spaced legs formed on said top plate and projecting toward said shoes in substantial vertical alignment therewith, horizontally spaced vertically extending links joining and universally mounted on said legs and shoes, and spring means between said links for urging the latter apart.

5. In a railway truck spring unit with a built-in snubber, the combination of, top and bottom spring plates arranged for relative vertical and horizontal movement, a housing upstanding from said bottom plate and presenting vertically disposed horizontally spaced walls, shoes horizontally spaced and arranged to frictionally engage said walls, horizontally spaced legs downstanding from said top plate in substantial vertical alignment with said shoes, link means horizontally spaced and connecting aligned legs and shoes, an articulated joint between each shoe and related link means, and spring means urging said link means into contact with said legs and shoes and said shoes into frictional engagement with said walls.

6. In a railway truck spring unit with a built-in snubber, the combination of, top and bottom spring plates arranged for relative vertical and horizontal movement, a housing upstanding from said bottom plate and presenting vertically disposed horizontally spaced walls, shoes horizontally spaced and arranged to frictionally engage said walls, horizontally spaced legs downstanding from said top plate in substantially vertical alignment with said shoes, link means horizontally spaced and connecting aligned legs and shoes, said link means being arranged for articulate movement relative to said legs and shoes, and spring means urging said link means into contact with said legs and shoes and said shoes into frictional engagement with said walls.

7. In a railway truck spring unit with a built-in snubber, the combination of, top and bottom spring plates arranged for relative vertical and horizontal movement, a housing upstanding from said bottom plate and presenting vertically disposed horizontally spaced walls, shoes horizontally spaced and arranged to frictionally engage said walls, horizontally spaced legs downstanding from said top plate in substantial vertical alignment with said shoes, link means horizontally spaced and connecting aligned legs and shoes, said link means being arranged for articulate movement relative to said legs and shoes, means on said link means extending into said shoes for limiting articulated movement therebetween, and spring means between said link means for urging the latter into engagement with said legs and shoes.

8. In a railway truck spring unit with a built-in snubber, the combination of, top and bottom spring plates arranged for relative vertical and horizontal movement, a housing upstanding from said bottom plate and presenting vertically disposed horizontally spaced walls, shoes horizontally spaced and arranged to frictionally engage said walls, horizontally spaced legs downstanding from said top plate in substantially vertical alignment with said shoes, horizontally spaced links connecting said legs and shoes for moving the latter vertically in response to a vertical movement of said top plate, said links being arranged for articulate movement relative to said legs and shoes, and spring means between said links for urging the latter against said legs and shoes.

9. In a railway truck spring unit with a built-in snubber, the combination of, top and bottom spring plates arranged for relative vertical and horizontal movement, a housing upstanding from said bottom plate and presenting vertically disposed horizontally spaced walls, shoes horizontally spaced and arranged to frictionally engage

said walls, horizontally spaced legs downstanding from said top plate in substantial vertical alignment with said shoes, horizontally spaced vertically extending links connecting said legs and shoes for moving the latter vertically in response to a vertical movement of said top plate, an articulate joint between each link and associated shoe, means on said links and shoes for limiting articulate movement therebetween, and spring means acting horizontally between said links for urging the latter into contact with said legs and shoes.

10. In a spring cap for use in a spring unit, a plate having spring seats spaced about said cap on one side of said plate, horizontally spaced legs extending from said plate from a side thereof including said spring seats, and partly spherical surfaces on said legs, said spherical surfaces being arranged to face one another in horizontally aligned spaced relation.

11. In a railway truck spring unit with built-in snubber, the combination of top and bottom spring plates, a group of coil springs acting between said plates, a housing upstanding from said bottom plate and presenting oppositely disposed walls, horizontally spaced friction shoes between and bearing against said walls, horizontally spaced connecting means movably connected to and joining each of said shoes and top plate, and spring means between said connecting means for urging said connecting means apart.

12. In a railway truck spring unit with built-in snubber, the combination of top and bottom spring plates, a group of coil springs acting between said plates, a housing upstanding from said bottom plate and presenting oppositely disposed walls, horizontally spaced friction shoes bearing against said walls, horizontally spaced connecting means movably connected to and connecting each of said shoes and said top plate, and a horizontally acting spring urging said connecting means apart and said shoes into frictional contact with said walls.

13. In a railway spring unit with built-in snubber and having top and bottom spring plates and a group of coil springs acting therebetween, the combination of a housing upstanding from said bottom plate, a shoe member frictionally engageable with said housing, a member downstanding from said top plate and spaced from said shoe member, connecting means extending between said members, said connecting means being angleably connectable to each of said members through interfitting surfaces on said members and means by lateral displacement of said means relative to said members, and spring means acting on said connecting means and urging said surfaces into contact for maintaining the connection between said means and each of said members.
